UNITED STATES PATENT OFFICE

2,191,644

ADJUSTABLE CHAIR

Isaac C. Decker, Montgomery, Pa., assignor, by
mesne assignments, to Reconstruction Finance
Corporation, Philadelphia, Pa., a corporation
of the United States

Application October 25, 1937, Serial No. 170,924

8 Claims. (Cl. 155—57)

The invention relates generally to chairs, preferably those of the heavily upholstered type designed to afford maximum comfort, and primarily seeks to provide a novel chair structure embodying base elements or supporting feet constantly engaging the floor, and a rigid seat, back and arm assembly or chair body unit, shiftable on the base elements by mere exertion of body pressure by a person sitting in the chair for varying the degree of tilt of said body unit, and held solely by frictional contact of the supporting and supported elements of the chair at the various positions to which adjustments are made. In its more detailed nature, the invention resides in the provision of a pair of longitudinal side members or supporting base elements, each provided at its respective ends with a front foot portion and a rear foot portion, and adapted constantly to engage the floor, a forwardly and downwardly inclined supporting surface preferably but not necessarily terminating in a depression or seat, and a rearwardly and downwardly inclined supporting surface; and a rigid chair body unit comprising a seat, back and arm assembly including at each side thereof a pair of supporting blocks spaced in the fore and aft direction and supported on and slidable along the supporting surfaces of the longitudinal base elements for the purpose of adjusting the degree of tilt of the body unit.

Another object of the invention is to provide a chair embodying a body unit and longitudinal base elements of the character stated in which the body unit is so constructed as to present longitudinal grooveways in which the base elements are received and laterally supported, and to position the center of gravity of said unit, whether empty or occupied by a seated person, intermediate of the fore and aft spaced supporting blocks, whereby an unusually stable adjustable structure will be provided in which precipitous tilting is impossible.

With the above and other objects in view which will more fully appear, the nature of the invention will be more clearly understood by following the description, the appended claims, and the several views illustrated in the accompanying drawings.

In the drawings:

Figure 1 is a side elevation of a chair embodying the invention, the chair back being illustrated in its most upright position, and the side member and supporting element contact being shown in dotted lines.

Figure 2 is a view similar to Figure 1 showing

the chair back in its maximum tilted position, one side rail of the seat frame being broken away along the line 2—2 indicated on Figure 3.

Figure 3 is an inverted plan view of the chair, one side member being removed from its supporting grooveway.

Figure 4 is a detail vertical cross section taken on the line 4—4 on Figure 2.

Figure 5 is a detail perspective view of one of the longitudinal side members or supports.

Figure 6 is a fragmentary detail side elevation with the body unit in the upright position shown in Figure 1 and the side rail removed as in Figure 2, a modified form of supporting block being shown.

In the practical development of the invention, I provide a seat, back and arm assembly forming a chair body tiltably adjustable as a rigid unit, by fore and aft sliding movement, on a pair of side members or base elements terminating at their ends in foot portions which constantly engage the floor. The body unit includes a seat frame box formed of side rails 5 and fore and aft transverse rails 6, a seat upholstery supporting structure 7, rigid arm structures 8, a back frame 9, and suitably styled heavy upholstery 10, all of which may be conventional in form.

A supplementary side rail 11 is secured in spaced parallel relation adjacent each side rail 5, and each rail 11 and the adjacent rail 5 form therebetween a grooveway or channel 12 in which a chair body unit supporting base element is received and laterally supported. The forward portion of the grooveway defining face of each side rail 5 is cut away or notched, as at 13, to form a grooveway enlargement which serves a purpose to be described hereinafter. About midway the length of each grooveway 12 a supporting block 14 is rigidly secured between the adjacent rails 5 and 11, and the supporting surfaces of these blocks are directed downwardly and are substantially semi-circular in shape, as at 15. These curved supporting portions of the blocks may be equipped with wear resisting or friction facings 16 if desired. Additional supporting blocks 17 are secured in a similar manner between and at the rear ends of the rails 5 and 11 and these are in the nature of segments presenting a quarter circle or less of supporting surface 18 presented downwardly and forwardly. The supporting surfaces 18 likewise may include facings 19 if desired. See Figures 2, 3 and 4 of the drawings.

The base equipment upon which the chair body unit is slidably adjusted includes a pair of lon-

35

55

itudinal side runners or base elements 20 each including an ornamental front leg or foot enlargement 21 and a rear foot enlargement 22. These supporting foot portions 21 and 22 constantly engage the floor, and it is unnecessary for the base elements 20 to partake of any movement incident to the adjustment of the chair to the various tilted positions of which its parts are capable of assuming. See Figures 2 and 5.

10 In Figure 5 of the drawings I have illustrated one of the base elements dismounted, and from this figure, and Figure 2, it will be apparent that each said element includes a forwardly and downwardly inclined supporting surface 23 disposed intermediately of the ends thereof and terminating forwardly in a rest depression or recess 24, and at its rear end with a rearwardly-downwardly inclined supporting surface 25.

15 The base elements 20 are received in the chair body unit grooveways 12 as shown in Figures 2 and 4, and the blocks 14 of the unit are supported on the element surfaces 23, 24, while the blocks 17 rest upon the surfaces 25. By sliding the unit rearwardly from the position shown in Figure 1 20 the blocks 14 will slide upwardly along the surfaces 23, and the blocks 17 downwardly along the surfaces 25, tilting the whole rigid unit to the maximum tilt shown in Figure 2 or to any intermediate degree of tilt desired. The seats 24 25 will limit sliding movement of the unit in the forward direction, and stop members 26 serve to limit movement rearwardly. It will be noted that the surface 23 inclines upwardly and rearwardly and the surface 25 inclines downwardly and rearwardly. The block 14 and the block 17 30 make sliding frictional contact with these inclined surfaces and therefore the body unit may be shifted by a person while seated thereon and no means is necessary for firmly holding the body 35 unit of the chair in the position to which it is shifted. The inclined portions 23 and 25 are disposed so that the center of gravity of the body unit and the weight of the person sitting on the chair is substantially in a vertical line passing 40 midway through the points of support of the body on the inclined surfaces. This greatly facilitates 45 the shifting of the body unit to different set positions. Then again, it is noted that the runner extends substantially from the front of the seat frame to the rear thereof and that there is a foot 50 at the front end of each runner and a foot at the rear end of each runner. These feet are always on the floor and are so positioned that when the chair is shifted to the position shown in Figure 1 55 there is no danger of a forward tilting of the chair. In other words, the weight is well distributed on four feet, for all positions of the body unit.

60 Removable pins are insertable through apertures in the rails 11 and into receiving sockets in the rails 5, one such pin being mounted beneath each base element 20, as shown in Figure 2 of the drawings. These pins prevent inadvertent removal of the elements out of the grooveways 12 65 and yet permit the free relative movement between the body unit parts and said elements necessary during adjustments of the chair. It will be observed by reference to Figures 2 and 3 that the enlarged fore foot portions 21 of the elements 20 are receivable in the notches 13 and by this means it is possible to provide attractive heavy appearing leg portions at the front of the chair.

70 By reason of the provision of the grooveways 75 12 suitable lateral support for the base elements

is provided and it is unnecessary to join these elements by cross bars or the like. Cross framing may be provided, however, if desired.

Easy chairs of the general character disclosed are of a somewhat personal nature; that is, they are selected to suit individual needs and tastes. A chair selected as extremely comfortable by one individual would not necessarily satisfy another. Thus it is particularly advantageous to have a chair such as I have disclosed, in which the tilt-position of the body unit can be conveniently altered by mere body pressure without need of the occupant arising from the chair, and without altering the relation of the associated seat, arm and back equipments. Chairs are selected by individuals for the comfort provided by a given relation of seat, arm and back structure, and it is a distinct disadvantage, in chairs affording tilt-adjustments, to have to resort to alterations of the relative positions of the seat, arm and back 20 equipments in effecting such adjustments. In my improved chair structure the adjustments are effected with a very limited amount of longitudinal shifting of the body unit on the base equipment, and in a manner rendering impossible 25 precipitous, dangerous tilting of said unit.

In order to avoid all possibility of the chair body unit tilting forwardly or rocking about the arcuate blocks 14, by placement of the weight of a user of the chair too far forwardly, the 30 blocks 14 may be equipped with forward extensions 28 shaped and positioned to overlie and rest upon the portions of the base elements forwardly of the seats 24, as shown in Figure 6 of the drawings.

35 What I claim is:

1. In a chair, a rigid body unit including a seat frame, arm and back portions; base equipment including longitudinal supporting elements constantly engaged with the floor; each said element including an upwardly-rearwardly inclined supporting surface midway its length and a similar downwardly-rearwardly inclined surface at its rear end; fore and aft spaced supporting blocks carried by said body unit and slidably supported on said surfaces; and means for limiting sliding movement of said blocks along said surfaces, comprising stop members engageable with the foremost blocks at the top of the upwardly-rearwardly inclined surfaces, and rest depressions at the bottom of said upwardly-rearwardly inclined surfaces.

2. In a chair, a rigid body unit including a seat frame, arm and back portions, said frame having longitudinal grooveways formed therein; base equipment including longitudinal supporting elements loosely fitting and laterally supported in said grooveways, said supporting elements extending substantially from the front of the seat frame to the rear thereof and having a foot at the forward and rear end of each supporting element constantly engaged with the floor; each said element including an upwardly-rearwardly inclined supporting surface midway its length and a similar downwardly-rearwardly inclined surface at its rear end; and fore and aft spaced supporting blocks mounted in the grooveways and including arcuate surfaces slidably supported on the inclined surfaces of said elements.

3. In a chair, a rigid body unit including a seat frame, arm and back portions, said frame having longitudinal grooveways formed therein; base equipment including longitudinal supporting elements loosely fitting and laterally supported in said grooveways and constantly engaged

with the floor; each said element including an upwardly-rearwardly inclined supporting surface midway its length and a similar downwardly-rearwardly inclined surface at its rear end; fore

- 5 and aft spaced supporting blocks mounted in the grooveways and including arcuate surfaces slidably supported on the inclined surfaces of said elements; and means for limiting sliding movement of said blocks along said inclined surfaces
 10 comprising stop members engageable with the foremost blocks at the top of the upwardly-rearwardly inclined surfaces, and rest depressions at the bottom of said upwardly-rearwardly inclined surfaces.

- 15 4. In a chair, a rigid body unit including a seat frame, arm and back portions, said frame having longitudinal grooveways formed therein; base equipment including longitudinal supporting elements loosely fitting and laterally supported in said grooveways, said supporting elements extending substantially from the front of the seat frame to the rear thereof and having a foot at the forward and rear end of each supporting element constantly engaged with the
 20 floor; each said element including an upwardly-rearwardly inclined supporting surface midway its length and a similar downwardly-rearwardly inclined surface at its rear end; and fore and aft spaced supporting blocks mounted in the
 25 grooveways and including arcuate surfaces slidably supported on the inclined surfaces of said elements; and means traversing the grooveways beneath the elements to prevent inadvertent removal of the elements without obstructing free
 30 relative movement between the elements and the body unit incident to adjustment of the unit positions.

- 35 5. In a chair, a rigid body unit including a seat frame, arm and back portions; base equipment including longitudinal supporting elements constantly engaged with the floor; each said element including an upwardly-rearwardly inclined supporting surface midway its length and a similar downwardly-rearwardly inclined surface at its rear end; fore and aft spaced supporting blocks carried by said body unit and slidably supported on said surfaces; and means for limiting sliding movement of said blocks along said surfaces, comprising stop members engageable with the foremost blocks at the top of the upwardly-rearwardly inclined surfaces, and rest depressions at the bottom of said upwardly-rearwardly inclined surfaces, and means engageable with the base elements forwardly of said depressions, for preventing forward tipping of the body unit when the foremost blocks are engaged in
 40 said depressions.

45 6. In a chair, a rigid body unit including a seat frame, arm and back portions; base equipment including longitudinal supporting elements constantly engaged with the floor; each said element including an upwardly-rearwardly inclined supporting surface midway its length and a similar downwardly-rearwardly inclined surface at its rear end; fore and aft spaced supporting blocks carried by said body unit and slidably supported on said surfaces; and means for limiting
 50 sliding movement of said blocks along said surfaces, comprising stop members engageable with the foremost blocks at the top of the upwardly-rearwardly inclined surfaces, and rest depressions at the bottom of said upwardly-rearwardly inclined surfaces, and rest extensions projecting forwardly from the foremost blocks and shaped to overlie and engage the base elements forwardly of said depressions when the foremost blocks are in the depressions for preventing forward tipping of the body unit about said foremost blocks.

55 7. In a chair, a rigid body unit including a seat frame, back and arm portions, runners at each side of said seat frame extending substantially from the front of the seat frame to the rear thereof, a supporting foot at the front end of each runner and a supporting foot at the rear end of each runner, each of said runners having an upwardly and rearwardly curved forward portion beginning midway between the forward and rear end of the runner and extending into a rearwardly and downwardly curved portion terminating adjacent the rear end of the runner, means having a sliding frictional contact, respectively, with the upwardly and downwardly curved portions for supporting said body unit and maintaining the same in different tilted positions.

60 8. In a chair, a rigid body unit including a seat frame, back and arm portions, runners at each side of the seat frame extending from the front of the seat frame to the rear thereof, a supporting foot at the front end of each runner and a supporting foot at the rear end of each runner, each of said runners having an upwardly and rearwardly extending forward portion and a rearwardly and downwardly extending portion adjacent the rear end thereof, means rigid with the seat frame and having sliding frictional contact, respectively, with the upwardly and downwardly extending portions serving as the sole support for the body unit, and means contacting with the runners in advance of the upwardly extending portion for limiting the forward shift of the seat frame on the runners.

ISAAC C. DECKER.
